UNITED STATES PATENT OFFICE.

CLAUDE H. FREESE, OF LOS ANGELES, CALIFORNIA, ASSIGNOR OF ONE-FOURTH TO
T. A. COLLINS, OF LOS ANGELES, CALIFORNIA, AND ONE-FOURTH TO CARL A.
LUNDBERG.

AIRSHIP.

Application filed April 12, 1927. Serial No. 183,115.

This invention relates to dirigible airships, in which planes serve as the principal lifting and carrying means of the airship while supporting facilities through gas are also embodied in this airship structure.

One of the objects of this invention is to stabilize a heavier-than-air dirigible by a proper distribution between planes and gas-carrying facilities.

10 Another object is to assure a proper control of the airship whether the ship is in the air or on the water surface by providing cabins above a certain level and above a proportionally large portion of the gas-holding body 15 of the ship.

Another object is to provide a deck, dividing the ship into lower and upper gas-holding compartments with controlling and passenger cabins above the deck.

20 Another object is to provide convex or un-round sections below and above the deck.

Another object is to provide controlling facilities throughout the length of the ship by which the gas-carrying facilities below and 25 above the deck can be controlled.

Another object is to provide a spine above and below the deck, braced and connected to the deck throughout the length of the ship, forming certain sections in which gas 30 containers are enclosed.

Other objects will appear from the following description and appended claims as well as from the accompanying drawings, in which—

35 Fig. 1 is a top plan view of an airship with planes and controlling means designed according to this invention.

Fig. 2 is a side elevation of Fig. 1.

40 Fig. 3 is a top plan view of the dividing deck, having the location of the main saloon and the passenger cabins indicated therein.

Fig. 4 is a general cross section through the dividing deck with the lower and upper convex hull portions, and the cabins outlined 45 therein.

Fig. 5 is a general cross section through the deck with braces in end elevation disposed in their proper relation to the deck within the contours of the hull, the hull being shown in 50 dotted lines.

Fig. 6 is a general cross section through the deck with an end elevation of the gas-

holding tanks or containers in their proper relation to the deck within the contours of the hull and the bracing members.

55

Fig. 7 is a general cross section through the controlling platform in its proper relation to the dividing deck, having also indicated therein the controlling pipe lines and valves for the several gas-holding containers.

60

The airship is principally designed to assure a safe operation on the surface of the water in case it becomes necessary for the airship to descend to the water when crossing the ocean. To facilitate a proper operation on 65 the ocean, the hull is designed to float on the water in a similar manner as any common ship with the lower portion of the whole ship, the airship in this case, submerged in water.

65

A dividing deck is therefore provided above 70 which all passenger and operating rooms are disposed. The whole structure is designed so that this dividing deck with the controlling and passenger rooms remain above the surface of the water and above the submerged portion 75 of the airship. The airship is therefore also designed to maintain its proper equilibrium, the lower portion of the ship being therefore designed heavy enough in proportion to the upper portions to maintain the airship in a 80 desired upright position when riding on the surface of the water.

70

The airship is also provided with suitable supporting gears, as wheels, by which the airship may ride over the surface of the ground. 85 This arrangement facilitates a starting and rising of the airship from the ground as well as from the surface of the water.

85

As illustrated in Fig. 4, the whole airship is divided into a lower portion 8 and an upper 90 portion 9 by a horizontally disposed deck 10. The deck 10 extends throughout the length and width of the airship.

90

Below the deck a spine 11 is provided from the front to the rear end near the bottom of 95 the ship. Another spine 12 is provided above the deck from the front to the rear end near the top of the ship. These spines are braced centrally to the deck as indicated at 13, and, furthermore, braced to points near the outer 100 edges of the deck as indicated at 14 in Fig. 5. The lower hull portion 15 is connected to the spine 11 and to the outer edges of the deck.

A promenade deck or passage way is

formed along the outer edges above the deck as indicated at 16, the deck being provided with a railing 17 on its outer edge as illustrated in Fig. 4.

From this promenade deck doors 18 lead into cabins 19 and a main saloon 20 in the deck structure. The saloon 20 is arranged in the forward part of the airship as illustrated in Fig. 3 in communication with a passage 10 way 21 and with the several cabins 19 as illustrated in Fig. 4.

The upper hull portion 22 is connected with the upper spine 12 and extends to the edges of the cabins along the outer edges of the airship as illustrated in Fig. 4.

Within the contours of the airship, that is within the inclosures of the hull portions and within the spaces left between braces 13 and 14, gas-holding containers 23 are arranged 20 above and below the dividing deck 10 as illustrated in Fig. 6.

The dividing deck is provided with control openings 25 through the larger portion of its length as illustrated in Fig. 3 to facilitate a 25 control of the gas containers. A platform 24 is therefore provided in suitable relation to the control openings in the deck as illustrated in Fig. 7.

Main pipe lines 26 are provided throughout 30 the length of the ship, having connections with control valves 27 at points to be reached from the platform 24.

The supporting gear consisting of wheels 28 and other braces by which the wheels are 35 applied to the underside of the hull as illustrated in Fig. 2 serves to support the whole airship structure when resting on the ground.

Planes are disposed above and secured to the upper hull portion 22 and to the deck 10 by 40 which the airship is largely raised into and maintained in the air. The planes are preferably spaced at various distances above the upper hull portion 22, planes 29_a being closer to the top of the hull than planes 29_b, as 45 illustrated in Fig. 2 to increase the carrying and lifting capacity of the planes.

One motor 30 with the propeller 31 is provided at the front end of the airship while other motors and propellers are provided at 50 various points along the sides of the airship. The motors 30_a with the propellers 31_a are preferably disposed at a certain angle in relation to the longitudinal axis of the airship different from the angle of the axis through 55 the motors 30_b with the propellers 31_b on the opposite side of the airship.

Elevators 32 and a rudder 33 are provided at the tail end of the airship of any common design customary on this type of airships.

Having thus described my invention, I claim:

1. An airship comprising a centrally disposed deck, a hull portion below said deck, another hull portion above said deck, planes

operatively connected to the airship above 65 said deck, operating means mounted on the deck, and compartments for passengers and the crew on the deck along the outer edge of said upper hull portion.

2. An airship comprising a centrally disposed deck, a spine extending from the front to the rear centrally above the deck, another spine extending from the front to the rear below the deck, a hull incasing said spine, planes above the deck, and propelling means 75 above the deck.

3. An airship comprising a centrally disposed deck, a spine extending from the front to the rear and above the deck, another spine extending from the front to the rear below 80 the deck, bracing members connecting the spines to the deck, a hull incasing the spines and bracing members above and below the deck, planes mounted above the deck, and propelling means mounted above the deck. 85

4. An airship comprising a centrally disposed deck, a spine extending from the front to the rear and above said deck, another spine extending from the front to the rear and below said deck, bracing members connecting 90 the spine to the deck, a hull incasing said spines and bracing members, gas containers disposed within the hull between the bracing members, planes mounted above the hull, and propelling means mounted above the deck. 95

5. An airship comprising a centrally disposed deck, a hull made in sections below and above said deck, the upper section of the hull terminating short before the outer contours of the deck forming a promenade deck around 10 the hull above the deck, planes mounted above the hull, and propelling means mounted above the deck.

6. An airship comprising a centrally disposed deck, a hull made in sections disposed 10 below and above the deck, the upper hull section terminating short before the outer contours of and above the deck, cabins for passengers and crew within the upper hull section along the outer edges of the hull, 11 planes mounted above the hull, and propelling means mounted above the deck.

7. An airship comprising a centrally disposed deck having control openings along its 11 middle, a platform in certain relation to said openings, a hull made in sections below and above said deck, gas containers in the hull embodying controlling means disposed to be reached through said openings from said platform, planes mounted above the hull, and propelling means mounted above the deck.

8. In an airship, a deck structure horizontally disposed with rooms for passengers and crew arranged along the edges of the deck 1 interconnected by passage ways and with a saloon in the middle crosswise through the deck connecting the oppositely disposed rooms.

9. In an airship, a deck structure horizontally disposed with rooms for passengers and crew arranged along the edges of the deck interconnected by passage ways and with a saloon in the middle crosswise through the deck connecting the oppositely disposed rooms, the said rooms and saloon being spaced from the outer edges of the deck forming a promenade above the deck, and doors by which said saloon and rooms may be entered from the promenade.
10. In testimony that I claim the foregoing as my invention I have signed my name.

CLAUDE H. FREESE.
